J. G. WILSON.

FIRE STOP FOR CORRUGATED METAL SHUTTERS.

APPLICATION FILED MAY 10, 1909.

968,623.

Patented Aug. 30, 1910.

UNITED STATES PATENT OFFICE.

JAMES G. WILSON, OF LARCHMONT, NEW YORK.

FIRE-STOP FOR CORRUGATED-METAL SHUTTERS.

968,623.

Specification of Letters Patent. Patented Aug. 30, 1910.

Application filed May 19, 1909. Serial No. 496,927.

To all whom it may concern:

Be it known that I, JAMES G. WILSON, a subject of the King of Great Britain, and a resident of Larchmont, Westchester county, State of New York, have invented certain new and useful Improvements in Fire-Stops for Corrugated-Metal Shutters, of which the following is a specification.

My invention relates to shutters of fire resistant material preferably of sheet metal and sliding in suitable guides or runways, and has particular reference to such shutters when of the well known corrugated type, whether the shutter be in one piece or in several pieces.

My invention is also applicable to such shutters whether arranged to open "straight away" or to be coiled, although I prefer the latter arrangement.

The object of my invention is, broadly speaking, to insure a closer (than is usual) junction between the shutter edges and the guides.

Shutters of the above generally described type are used to protect door and window openings in case of fire, and are either thrown into place by intention or, in many cases, automatically. Complete protection from fire properly means not only protection from direct action of the flame and transference of heat, but should also include a complete cutting off of smoke and vapors, the effect of which, in many cases, is more damaging to merchandise as well as more dangerous to life, than the fire itself.

So far as I am aware, shutters of the above mentioned type as heretofore made have had openings or passage ways of considerable aggregate area between the shutter edges and their inclosing guides, thereby readily permitting the smoke, flame or vapor laden air to pass around such shutter edges or across the door or window opening into the room or rooms to be protected. This has necessarily resulted by reason of the fact that lateral play between the shutter edges and the guide bottoms, and transverse play between said edges and the groove sides has been required to make the shutter normally operable without excessive friction.

I accomplish my invention by placing on one or both sides of each shutter, at each edge thereof and in each corrugation, a permanently attached metal stop or abutment which substantially fills said corrugation at the edge so as to fill the space bounded by

the bottom and sides of the groove and the adjacent side of the embracing guide. This stop takes the form of a block which may be either solid or hollow and which, although 60 it may only incompletely bridge (with the shutter) the space between the guide walls thereby not materially increasing the sliding friction over that which obtains for the shutter alone without my stops may yet be 65 sufficiently long (*i. e.*, in the direction of the shutter's width) to introduce excessive air friction and thus substantially seal the passage.

Referring to the drawings, Figure 1 illustrates, in section, a portion of a preferred form of corrugated shutter showing my stops in place; Fig. 2 is a similar section to smaller scale showing the relation of the individual steps to their corrugations when 75 the shutter is coiled; Fig. 3 is a perspective view of one of the stops removed from the shutter; and Fig. 4 is a section taken along the line 4-4 of Fig. 1.

A is a flexible metallic shutter uniformly 80 corrugated as *a*, *b*, and B one of the lateral guides or runways in which the shutter normally slides.

C is a roll or drum, controlled in any suitable way as is well known in the art, 85 upon which the shutter is coiled when its opening is cleared.

On one or both sides of the shutter at each edge and in each corrugation is my stop D. This should be of fire resistant material, 90 preferably either a solid or hollow casting. This block is, in section, substantially three sided, two of the sides *c*, *d*, converging from a straight side *e* so as to conform to the shape of the corrugation, said sides merging into 95 one another so as to form a curved apex *e'* also conforming to the groove at its bottom. The depth or thickness of the block from its apex to the straight side *e* is substantially the depth of the corrugation, and when the 100 block is properly set, the straight side *e* is parallel with the sides of the guide and substantially in line with the highest points of the shutter on the side under consideration.

The length of the block (in the direction 105 of the shutter's width) is preferably about equal to the depth of the guide in which the shutter moves. In practice, I prefer to form upon the end of each block, away from the shutter edge, an extension or projection *f* 110 which in section conforms to the groove just as does the block proper, but the depth of

said extension is only about one half that of the block, the function of the extension being purely to assist in fastening the block to the shutter and in steadyng the same thereon.

5 To fasten my improved stop to the shutter I drill two holes *g* and *h* at right angles to the face *e* and in the center line of the stop and its extension respectively, and into 10 these holes I place rivets *h'* which are upset in corresponding holes piercing the bottoms of the corrugations. By fastening the stop in this manner, it exercises no constraint whatever upon the shutter, and the latter 15 will readily coil upon its drum *C*.

As described and if placed on one face only of the shutter the stops do not entirely close the free spaces at the shutter edge so as to prevent transmission of smoke and 20 gases around such edge, and the spaces between the corners *i*, *j*, of the blocks are left uncovered; but, in practice, I find that from 75% to 85% of the total originally open spaces may thus be blocked off so that the 25 passage of fire, smoke and hot gases is substantially prevented or, at any rate, greatly diminished. If stops are, however, placed in each corrugation on each face of the shutter it is possible to block off all the edge 30 space. This may be done nicely and is, indeed, preferable on a shutter sliding "straight away" but on a shutter intended to coil I prefer the stops placed only on the outer face of said shutter (*i. e.* on the 35 face away from center of coil *C*) as, so placed, the shutter retains a maximum of flexibility the sides of the corrugations opening away from the stops upon the outside of the coil (see Fig. 2) and similarly approaching upon the inner face of the shutter 40 next said coil as the shutter is coiled where-

as with stops on the inner face only or on both faces of the shutter this approach of the walls of the corrugations on said inner face is not possible by reason of the stops which have been made to completely fill said corrugations; the shutter is therefore stiff and hard to roll as compared with its condition when the stops are on its outer face only.

45 My invention is effective, simple and easy to apply and

Having now fully disclosed the same I hereby claim—

1. In a corrugated fire resistant shutter, 55 sliding in guides, individual fire stops in the corrugations at the shutter edges, said stops lying wholly within the shutter edge, substantially as and for the purpose described.

2. In a corrugated fire resistant shutter, 60 sliding in guides, individual fire stops in the corrugations at the shutter edges, said stops lying entirely on one side of said shutter, substantially as and for the purpose 65 described.

3. In combination, a corrugated fire 70 resistant shutter, parallel guides arranged to engage the edges of said shutter, and a plurality of individual fire stops in the corrugations and within said guides, each of said stops lying wholly within the shutter edge and wholly on one side of said shutter, substantially as and for the purpose described.

In testimony whereof I have hereunto set 75 my hand in the presence of two subscribing witnesses.

JAMES G. WILSON.
